CIGARETTE LIGHTER, OR SIMILAR ARTICLE

Dieter Rams, Konigstein, Germany, assignor to Braun Aktiengesellschaft, Frankfurt am Main, Germany, a corporation of Germany

Filed Dec. 6, 1968, Ser. No. 14,834

Claims priority, application Germany June 6, 1968

Term of patent 7 years

Int. Cl. D27—05

U.S. Cl. D48—27

Fig. 1

Fig. 2

Fig. 4

FIG. 1 is a perspective view of a cigarette lighter, or similar article, showing my new design including a housing for the cigarette lighter, an operating handle, and an aperture for the flame;

FIG. 2 is a side perspective view thereof, the opposite side being substantially the same in appearance;

FIG. 3 is an end elevational view thereof; and

FIG. 4 is a top plan view thereof.

The bottom of the cigarette lighter or similar article is plain.

I claim:

The ornamental design for a cigarette lighter, or similar article, substantially as shown and described.
